(57) **CLAIM**

We claim the ornamental design for a toy clip, as shown and described.

DESCRIPTION

FIG. 1 is a front perspective view of the toy clip showing my new design.

FIG. 2 is a front side view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The broken lines in the figures are for the purpose of illustrating portions of the toy clip and form no part of the claimed design.

1 Claim, 4 Drawing Sheets
